(57) CLAIM

The ornamental design for a battery display package, as shown and described.

DESCRIPTION

A portion of the disclosure of this design patent document contains material which is subject to copyright protection. The copyright owner has no objection to the facsimile reproduction by anyone of the patent document or the patent disclosure, as it appears in the United States Patent and Trademark Office patent file or records, but otherwise reserves all rights under the copyright laws of the United States (17 U.S.C. §106).

FIG. 1 is a perspective view of a battery display package, in accordance with the present invention.

FIG. 2 is an exploded perspective view thereof.

FIG. 3 is an exploded front view thereof.

FIG. 4 is a top view thereof.

FIG. 5 is a bottom view thereof.

FIG. 6 is a right side view thereof with the opposite side view being a mirror image thereof; and,

FIG. 7 is a back side view thereof.

FIGS. 2, 3, 6 and 7 are drawn in reduced scale.
